UNITED STATES PATENT OFFICE.

FRIEDRICH DESSAUER, OF FRANKFORT-ON-THE-MAIN, GERMANY.

APPARATUS FOR MAKING INSTANTANEOUS X-RAY PHOTOGRAPHS.

1,096,692.

Specification of Letters Patent.

Patented May 12, 1914.

Original application filed November 8, 1909, Serial No. 526,795. Divided and this application filed August 3, 1911. Serial No. 642,181.

To all whom it may concern:

Be it known that I, FRIEDRICH DESSAUER, a subject of the King of Bavaria, residing at Wildungerstrasse 9, Frankfort-on-the-Main, Germany, have invented certain new and useful Improvements in Apparatus for Making Instantaneous X-Ray Photographs, of which the following is a specification.

This invention relates to an apparatus for making instantaneous X-ray photographs and has particular reference to an improvement in means for exposing photographic plates used in connection with X-ray photography the subject-matter of this application forming a division of a copending application for patent, Serial No. 526,795, filed Nov. 8, 1909.

The object in view in this connection is to construct an X-ray photographing apparatus which is capable of effecting an extremely rapid exposure of the photographic plate as well as to simplify the structure of such a mechanism. With this object in view, the invention will hereinafter be fully set forth and described, reference being had to the accompanying drawing, in which one embodiment of my invention is shown.

For some time efforts have been made to shorten the length of time required for taking X-ray pictures, so as to render it possible to take a truly instantaneous picture. By some apparatuses so-called "instantaneous" pictures are taken in from one to ten seconds, and exposures of as much as twenty seconds have been considered as instantaneous. In a few isolated cases pictures have been taken in less than one second, ranging in time from one-quarter to one twenty-fifth of a second. Even the latter cases, however, do not really come under the head of instantaneous exposures, and one can only call an exposure "instantaneous," when the period of light, with reference to the rapidity of the movement of the object to be photographed, such, for instance, as the beating heart, or voluntary or involuntary movements of the muscles, is of short duration.

Thus, a practical instantaneous exposure is one which is made in, at the most, one fifth of a second, and generally ranges from one hundredth to one three-hundredth part of a second. In radiograms taken with the apparatus described herein the outlines

of the beating heart show absolutely sharp on the plate.

Pictures taken by the old methods, and ranging, as stated, from one to twenty second exposure, have almost invariably been secured by apparatuses in which were used a powerful direct current induction coil and a Wehnelt interrupter or less frequently, a mercury interrupter, the secondary high tension alternating current being transformed into high tension continuous current. There might be mentioned another experiment in which the effect of an interruption was increased to such an extent by an acceleration of the rapidity of the interruption that a radiogram could be taken by means of a single interruption. To this effect a wire closing the circuit of the primary coil was shot through by means of a pistol. All these methods are however imperfect.

The last mentioned method is not suitable because a certain period of time will always pass between the voluntary closing of the primary circuit and its voluntary interruption. This period is not controllable respecting the necessary duration of the magnetizing current, and the ohmic resistance of the circuit being only 0.1, an insufficient current strength will be obtained in putting into circuit safety resistances, or an inadmissible growth of the current strength will result if no safety resistances are used.

The present invention, by which the pictures have been made with exposure ranging from 1/100 to 1/300th second, is based on the single excitement of the secondary coil of a transformer by the interruption of the primary continuous current, and a high tension transformer is used for that purpose, said transformer being constructed similar to a simple induction coil. Furthermore, it uses continuous current, but, in contradistinction to other apparatus, no continuously operating interrupter is made use of. The use of an ordinary interrupter makes an instantaneous exposure impossible, and instantaneous photographs are successful with the herein described apparatus, chiefly, because a single impulse of discharge current is used, the duration of which with the high potential transformer lies between 1/50 and 1/300th of a second.

The drawing shows a diagrammatic out-

line of the apparatus, with the circuits thereof.

In the accompanying drawings, which represent one form of the invention, *a* is the direct current transformer or induction coil and has one pole of the primary coil connected to one side of a current source *s*. A condenser *b* is connected with one pole in contact with the other terminal of the primary coil of the transformer *a*, and is furnished of suitable size so that when the primary circuit is broken, the strength of the discharge of current can be raised by the diversion of the current to said condenser 10 and thence back over the line, producing in the secondary coil an induced current of very high voltage capable of ionizing the X-ray tube. The interval of time between the making and the automatic breaking of the circuit which is completed as hereinafter described is a very short one and depends particularly upon the length of time which is required to withdraw a contact element from a mercury bath. At the instant of withdrawal 15 of said contact from the mercury bath, a momentary resistance is set up in the primary circuit, during which said condenser becomes charged, said charge, as stated, going back over the line when the break in the circuit is made.

In the circuit established between the primary coil of the transformer *a*, the current source *s'*, and the condenser *b* is an automatic switch *c*. Said switch is, or may be, of 20 the lever type or of any other kind and consists of an arm *c'* and a leaf which may enter the fixed contact members, the latter being connected to the condenser terminal. The switch *c* co-operates with a mechanism 25 by means of which it is rendered possible to utilize the single impulse of discharge current. The contents of a mercury vessel *d* is connected by means of a suitable immersed fixed terminal into the primary circuit between the part *g* of the switch *c* and the condenser *b*. Immersed in the mercury of the vessel *d* is a movable contact rod *f* which is adapted to be raised out of the mercury by 30 means of the expansion spring *e*. The upper end of the rod *f* is provided with a fixed collar or projection *f'* with which a latch or tappet *h* is adapted to engage to hold the rod *f* in its depressed position. The tappet *h* is connected to or carried by the switch 35 arm *c'*, so that the movement of the tappet is governed by the action of the latter. Thus, when the switch arm *c'* is thrown over to close the primary circuit the tappet *h* is withdrawn from the collar or projection *f'*, 40 and the rod *f* is permitted to snap upwardly under action of the spring *e*. In the connection between the tappet *h* and the switch *c* is inserted a regulating screw *i*, by means of which the length of the connection can be 45 adjusted, and consequently the interval of

time which elapses between the closing of the switch *c* and the releasing of the rod *f*.

The duration of the closing of the circuit must be adjustable, *i. e.* it must be brought into accordance with the necessary duration of the magnetizing of the induction coil, no matter whether the means for this adjustability are provided in the apparatus itself or whether they are added to the apparatus 70 separately.

In the above described manner the primary circuit is closed by means of the switch *c* for a period of time which depends first upon the length of the tappet *h* adjustable by means of the screw *i*, secondly upon the length of the rod *f* which is immersed in the mercury, and thirdly upon the acceleration exercised by a spring *e* or by another starting device. This period of time being an extremely short one, it is possible to over-load the machine to a high degree with safety, and the required impulse of current to cause a single intense excitement of the secondary coil is attained. Thus, it is obvious that the solution of the problem of instantaneous X-ray photography, as contemplated in this invention, depends on the possibility of a momentary high carrying of current, under the protection of the circuit current against excessive overloading, 90 and the principal feature of this invention lies in this, that after the switching on of the current, a forceful switching off is caused after a time which is equal to the necessary duration of the magnetizing current, and which allows a high overloading 95 without danger.

As already stated, it is possible to over-load electric machines for a very short interval of time to the extent of a few hundred per cent., and by this apparatus, the overloading is carried out without danger to the machine, by the almost simultaneous opening of the circuit. The discharge current strength can be raised by the transference of a current of a sufficiently high strength through the transformer and the condenser of suitable size so that any desired X-ray exposure can be taken by a single discharge impulse.

The characteristics of the present invention are: (1) The voluntary switching on of the apparatus is immediately and automatically followed by an interruption of the primary circuit, by means of the apparatus as described herein. (2) This interruption produced automatically by the closing of the primary circuit permits in the primary of a very high load admissible only for a very short time. (3) The interruption at break 110 produces the desired current impulse in the secondary. (4) The phenomenon is produced only once by one switching on of the apparatus. (5) As exciting current a direct current is used. (6) There are two circuits, 120

an inducing and an induced one. (7) No continuously working break is being made use of.

What I claim is:—

- 5 1. In an apparatus for taking instantaneous X-ray photographs, the combination of a direct current transformer, a high capacity condenser in circuit with the primary of said transformer and a current source, a switch in the circuit, and means mechanically controlled by said switch to break the primary circuit at high load within a short adjustable interval of time after the switch is closed.
- 10 2. In an apparatus for taking instantaneous X-ray photographs, the combination of a direct current transformer or induction coil, a high capacity condenser in circuit with the primary of said transformer and a

current source, a switch in the circuit, and means mechanically controlled by said switch to break the primary circuit at high load within a short adjustable interval of time after the switch is closed, said device consisting of a mercury cup, a spring pressed contact immersed in said cup and a releasing mechanism operatively disposed between said switch and said spring-pressed contact, whereby the latter is released to spring out of said cup when said switch is closed interrupting the primary circuit.

In testimony whereof I affix my signature in presence of two witnesses.

FRIEDRICH DESSAUER.
